UNITED STATES PATENT OFFICE.

FORDYCE A. LYMAN, OF CLEVELAND, OHIO.

GAS-GENERATOR.

SPECIFICATION forming part of Letters Patent No. 275,677, dated April 10, 1883.

Application filed January 12, 1883. (No model.)

To all whom it may concern:

Be it known that I, FORDYCE A. LYMAN, of Cleveland, in the county of Cuyahoga and State of Ohio, have invented certain new and useful 5 Improvements in Gas-Generators; and I do hereby declare the following to be a full, clear, and exact description of the invention, such as will enable others skilled in the art to which it pertains to make and use the same.

10 My invention relates to improvements in gas-generators; and it consists in certain features of construction and combinations of parts, as will be hereinafter described, and pointed out in the claims.

15 The object of my invention is provide an apparatus that will generate gas in larger quantities than those devices known as "vapor-burners." In the latter class the generating and consuming the gas are usually accomplished in 20 the same device, while my new device is designed to supply gas for light or heat at points remote or near to the generator.

25 In the drawings, Figure 1 is a vertical sectional view of a gas-generator that embodies my invention. Figs. 2 and 3 are views in detail of portions of Fig. 1.

30 A is a retort, preferably tubular, and expanding laterally into a broad vaporizing-chamber at A', and terminating above in the end a, 35 that may be made detachable. This end is provided with the valve a' and a threaded projection at a², suitable for attaching a discharge-pipe. The lower end of the retort is provided in the usual manner with a supply-pipe at 40 a³, and the drip-tube a⁴. Directly under the chamber A' is placed the air and vapor commingling and combustion chamber B. This chamber has an annular opening on top around the retort A, and is provided with a ring of 45 perforated metal, b², extending from the edge of the chamber around said opening to the bottom of the chamber—in fact, dividing the chamber into two parts. The chamber B is provided with the opening b, that may be made funnel-shaped, if so desired, and also with the tube b', when necessary. The chamber B may be modified in size and shape, as shown in Fig. 2 at B'. In fact, the only limit to extending it 50 in this direction is the length of the tubular part of the retort A. To some part of the re-

tort—preferably the chamber A'—is attached the hollow arm C. This arm is provided with the valve c, that is so arranged as to discharge gas through the opening b into the chamber B. To the arm C is also attached 55 the tube c', leading under the said arm, and provided at c² with a mouth-piece, that is better shown in enlarged section view, Fig. 3, in which are shown the orifices c³, where air is admitted to commingle in the enlarged mouth-piece with the gas from the tube c'.

The operation of my device is as follows: A quantity of hydrocarbon oil having been admitted to the retort A through the supply-tube a³, heat is applied to the arm C and the 60 adjacent parts until sufficient gas is formed to pass from the valve c through the opening b into the chamber B and support combustion therein. After this the external heat is discontinued, as the device will then be self-operating. Vapor from the vaporizing-chamber 70 A' is by means of the hollow arm C and the valve c projected through the opening b into the chamber B. The opening b is somewhat large as compared with the size of the jet of 75 vapor aforesaid issuing from the valve c. By reason of the force of this jet and the size and shape of the opening b, a large quantity of air is drawn into the chamber B, where it is commingled with the said vapor, and is forced 80 through the perforations in the plate b² into that portion of the chamber immediately surrounding the retort. Here, coming in contact and commingling with more air, the product of air and vapor is ignited. The current of 85 air and vapor through the perforated plate b² is such as to press the burning mass against and wrap it around the tubular portion of the retort, and in this condition it passes up until it comes in contact with the broad chamber 90 A', where an intense heat is concentrated and a large amount of it absorbed into the said chamber A', forming gas in the retort rapidly.

In a former device for which Letters Patent No. 255,553 were granted in March, 1882, a 95 chamber similar to B was shown, but operating only as a commingling-chamber. The perforated cylinder extended from the top of the chamber to a plate above, and the combustion took place outside of the said perforated cylin- 100

der, instead of inside the chamber B and the perforated cylinder and next to the retort A, as is the case in any new device.

When light oil is used no auxiliary burners or combustion is necessary. When heavy oils are used it will be necessary to apply heat to the arm C, in order to prevent the condensation of gas in this part. For this purpose I have the bent tube b', leading from the commingling-chamber B under the arm C, and through which the product of commingled air and gas is conducted and burned under the said arm. Also, I have the tube c', conveying gas from the generator A', and burning it also under the said arm, first, however, combining and commingling it with suitable quantities of air in the mouth-piece c², heretofore described. Either or both or neither of these tubes may be used to keep the arm C at the proper temperature. The use of these auxiliary heaters will depend entirely upon the kind and gravity of the oil used in the retort.

In using the enlarged commingling and combustion chamber B', as shown in Fig. 2, good results may be obtained by leaving out the perforated plate b². In this case the combustion takes place generally through the chamber B', surrounding and coming in direct contact with the retort A.

It is evident that by extending the chamber as shown at B', Fig. 2, a larger surface of the retort A will be inclosed in the said chamber, and consequently will be enveloped in the burning vapors that fill the chamber, and thus will be generated a greater amount of gas in the retort A. For all ordinary purposes, however, I prefer the perforated ring b², as causing better combustion and giving more satisfactory results generally.

What I claim is—

1. In a gas-generator, the combination, with

the retort terminating at its top in a laterally-extended generating-chamber, of the pipe-connection and valve connected with said chamber for connecting with an external supply- 45 pipe, and suitable pipes and valves for transferring gas from the generating-chamber to the combustion and combining chamber independently of the external supply-connections, substantially as described. 50

2. In a gas-generator, a chamber inclosing a portion of the retort, and provided with an opening on top, around the said retort, and divided by a perforated cylindrical plate into two parts, the outer part forming a commingling-chamber and the inner part next the retort forming a combustion-chamber, substantially as shown and described. 55

3. In a gas-generator, the combination, with the commingling and combustion chamber B, 60 provided with the perforated partition b², of the enlarged vaporizing-chamber A', forming a part of the retort, and so situated as to receive the volume of heat as it issues from the chamber B, substantially as and for the purpose set forth. 65

4. In a gas-generator, the combination, with the retort and its extended generating-chamber and the combustion and combining chambers surrounding said retort and having the opening b, 70 of the hollow arm C, provided with valve c, pipe c', leading from said hollow arm, and the pipe b', leading from the combustion and combining chamber and terminating adjacent to the end of said pipe c', substantially as described. 75

In testimony whereof I sign this specification, in the presence of two witnesses, this 6th day of January, 1883.

FORDYCE ALLEN LYMAN.
